WILLIAM R. ZIMMERMAN, OF CLEVELAND, OHIO, ASSIGNOR TO THE BISHOP & BABCOCK MANUFACTURING COMPANY, OF CLEVELAND, OHIO, A CORPORATION OF OHIO.

THERMOSTATIC VALVE.

Application filed April 7, 1926. Serial No. 100,278.

The present invention, relating, as indicated, to thermostatic valves is more particularly directed to an improved thermostatic valve for use in conjunction with the circulatory system of an internal combustion engine. One of the principal objects of the invention is the provision of an extremely simple device of this character, and one having few parts. A further object is the provision of a thermostatically controlled valve which operates to control the flow of the circulatory medium, and is provided with means for causing an opening of the valve upon failure of the thermostatic element and by reason of the pressure exerted upon the valve by the circulatory medium.

To the accomplishment of the foregoing and related ends, said invention, then, consists of the means hereinafter fully described and particularly pointed out in the claims; the annexed drawing and the following description setting forth in detail certain mechanism embodying the invention, such disclosed means constituting, however, but one of various mechanical forms in which the principle of the invention may be used.

In said annexed drawing:—

Fig. 1 is a view more or less diagrammatic of an internal combustion engine, cooling means and circulatory system in which is disposed my improved valve; and Fig. 2 is a transverse section through the valve.

Referring now to Fig. 1 there is shown an internal combustion engine 1 which is provided with the usual cooling jackets, (not shown), one for each of the cylinders of the engine, these jackets discharging at their upper ends into a manifold 2. Extending from the discharge port in the manifold is a circulatory conduit 3 which leads to the upper portion of a cooling means, consisting of a radiator 4. The cooling liquid, which is usually water, is forced up through the conduit 3 to the top of the radiator and then flows downward through the radiator. From the bottom of the radiator there extends a lower conduit 5 leading to a circulating pump 6, by means of which the water is drawn from the radiator through the conduit 5, and through a second conduit 7 which leads to the lower portions of the various jackets around the cylinders.

The pump 6 may be operated in any usual manner.

Interposed in the upper circulatory conduit 3 is my improved valve mechanism, which is shown in Fig. 2. My improved valve includes a housing 10, in which is disposed a valve seat 11, against which is seated a valve 12 which closes the housing, and also the conduit, to flow. The valve is secured to a stem 13 which extends through a suitable guide or bearing 14 in arms 15 which are formed from the same disk which constitutes the seat 11, being bent inwardly to allow the use of a flat disk valve, and being spaced to permit the flow of water around them. The valve has a free effective area on its upstream side which extends to the inner edge of the contact of its circumferential portion with the flat portion of the valve seat. The stem 13 is secured to, and sealed within, the head 16 of a hollow resilient, expandible and contractible element 17, which, for convenience, will be hereinafter referred to as a metallic bellows. The other end of this bellows is sealed and secured to a disk or partition 18 extending transversely of the chamber and provided with a series of ports 19 adjacent its circumference, permitting the constant flow of water therethrough.

The metallic bellows 17 is filled, under a pressure less than atmospheric pressure, or to what will be designated a subnormal pressure, with a small quantity of a volatile liquid which will volatilize and expand at a predetermined temperature, the expandibility of the fluid causing an expansion of the bellows and the consequent movement of the valve 12 away from the seat 11, thus permitting flow through the casing 10 and conduit 3. The flow is in the direction of the arrows 20. The metallic bellows is also so proportioned and disposed with respect to its mounting on the disk or partition 18 that when the valve 12 is closed the bellows will either be in a normal condition, that is, neither expanded nor contracted relatively to its condition at atmospheric pressure, or in a slightly expanded condition, thus giving a slight tension, which tends to keep the valve on its seat. In addition to this tension there is of course the difference in pressure acting against the effective area of

the end 16 of the bellows. There is a substantial vacuum within the bellows and atmospheric pressure outside, the difference in the two pressures multiplied by the effective area of the disk 16 giving an additional pressure which tends to keep the valve on its seat so long as the bellows wall is intact.

In the normal operation of my device 10 when the engine is started water is forced up through the conduit 3 through the ports 19 and around the bellows wall 17. When the temperature of this water has reached the predetermined temperature which is effective 15 to cause volatilization of the fluid inside the bellows the water acts to expand the bellows, moving the valve 12 from its seat and permitting flow through the conduits 3 to the radiator. The valve of course 20 remains open as long as the water is at the predetermined temperature or above.

In the event of a microscopic leak in the wall of the metallic bellows, which sometimes occurs without permitting any rapid filling of the bellows by the circulatory medium, it is sometimes desirable to cause the valve to move to an open position to prevent an excessive increase in temperature in the water jackets and resultant injury to the cylinders. In the present construction this action is secured by the proportion of the size of the bellows, that is, the effective operating area of the bellows and the area of the valve 12, the latter being made larger than the effective area of the bellows by an amount determined by the water pressure which will normally exist in the conduit and through the casing 10, and which will act of course to produce a pressure on the upstream side of the valve 12 tending to open it. The effective area of the bellows extends across the central portion thereof to a circumference approximately midway of the corrugations about the body of the bellows. If a microscopic leak develops in the bellows wall and the vacuum therein is lost there will then be a force acting to hold the valve open, or to open the valve if closed, which will be the difference in pressure exerted on the down-stream side of the movable end of the bellows and the upstream side of the valve 12. As the valve 12 has the greater area the pressure will open, or tend to hold open, this valve, thus preventing any stoppage of the circulation and any injury to the engine. If the circulation is maintained by a pump which produces a high pressure then a relatively small differential in the effective area of the bellows and in the area of the valve will be sufficient to produce this opening action, while a lower pump pressure will of course require a greater differential in these areas. Unless the bellows is filled with a circulatory medium the valve will either open or remain in

that condition since then the pressure will be balanced on both sides of the moving end of the bellows and the full area of the valve will be effective to maintain it in an open position.

The form of casing shown is particularly adapted for insertion in a rubber hose line, or hose line of similar type, the ends 24 and 25 being corrugated to permit the effective clamping within the ends of the conduit 3 by 70 any suitable means, while the joint 26 between the forward and rear parts of the casing is formed by spinning over the flange 27, which clamps tightly together the outer edge of the disk 11 and the out-turned flange 28 on the forward edge of the casing 10 proper. The partition or disk 18 is securely and accurately seated by being engaged within a recess 29 formed in the body 10 followed by the spinning inward of a slight 80 ridge 30, which locks this partition in place and in a certain spaced relation to the forward partition, in which is formed the valve seat 11.

The combined guide and valve seat 11 is 90 formed from a single sheet of metal and serves both the purpose of a seat for the valve 12, a guide for the stem 13 and a stop limiting the outward movement of the bellows and valve and preventing the valve, in 95 the event of a rupture of the bellows wall, from ever moving far enough outwardly or in a down-stream direction to engage the casing thus partially or completely stopping the circulation of the cooling medium. One 100 of the advantages of this construction just referred to is that it combines in a single element various desirable or central features in such a construction, and in this way simplifies the entire construction and reduces the number of parts. It should be noted that even though the various features of my invention, such as the one just referred to and others previously described, are employed it is still possible to employ a valve 105 having a less area than the effective area of the bellows, although in such a construction the bellows must be filled at a materially higher pressure because the normal tendency of such a construction is to remain closed, and there is a differential pressure in the 110 circulating medium which must be overcome by an increased pressure in the bellows before the valve can be moved to an open 115 position.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In combination a circulatory conduit, a 130

- valve disposed therein to control flow therethrough, said valve opening downstream therein, and a sealed hollow resilient element disposed on the upstream side of said valve
- 5 and connected thereto, said element containing a volatile fluid at subnormal pressure, said element expanding to open said valve, and said element then exerting a closing pressure upon said valve consisting of the 70
10 subnormal confined pressure plus any tension in the element, and the area of said valve being greater than effective area of said element, whereby a puncturing of said element allows the pressure of circulatory 75
15 liquid to overcome the resistance of said valve to opening.
2. In combination, a circulatory conduit, a valve seat therein, a valve disposed in said conduit on said seat to close the same against 80
20 flow, said valve opening downstream, a hollow expansible and contractible element disposed in said conduit on the upstream side of said valve connected to the same, said element containing a volatile fluid at less than 85
25 atmospheric pressure, the effective area of said element being less than the effective area of said valve.
3. In a device of the character described, the combination of a casing having two portions abutted end to end, one of said portions having an outwardly extending flange and an encircling recess in its inner wall at a point spaced from said flange, an apertured partition disposed transversely of said casing 90
30 and having its outer periphery disposed adjacent said flange, and the other of said two portions having a flange extending over and clamping together, said flange on said first named portion and said partition, a second apertured partition disposed transversely of said casing and sealed into such recess in the wall thereof, and a thermostatically controlled valve mounted in said casing on said last named partition and seating against said first named partition. 95
40
4. In a device of the character described, the combination of a casing having oppositely disposed ports and an enlarged intermediate portion, provided with two encircling spaced recesses in its inner wall, two apertured partitions mounted and sealed in said recesses, one of said partitions having a central valve opening therein, and the other one or more constantly open ports, a valve 100
50 mounted on the side of said first named partition away from said second partition in position to close the opening therein, and a thermostatic element mounted on said second partition and disposed between that and the other partition, and means connecting said element and said valve for operation. 105
55
5. In a device of the character described, the combination of a casing having oppositely disposed ports, a thermostatically con- 110
60
- trolled valve mounted in said casing and disposed longitudinally therein, and an element disposed transversely in said casing, said element being provided with a portion forming a seat for said valve and with another portion constituting a guide controlling the direction of movement of said valve and acting as a stop limiting the movement of said valve in one direction. 115
65
6. In a device of the character described, the combination of a casing having spaced ports, two spaced transverse partitions secured to the inner walls of said casing, said partitions being apertured to permit liquid flow therethrough, a hollow imperforate thermostatic element secured at one end to one of said partitions, a valve, a stem connecting said valve to said thermostatic element, and the other of said partitions being provided with a recessed portion provided with a central hub having an opening therein, in which is slidably received said stem, said last-named partition acting as a seat for said valve and said hub serving as a guide for said stem and said hub serving as a guide for said stem and a stop element 120
70 limiting the movement of said stem and valve in one direction. 125
75
7. In apparatus of the character described, the combination of a circulatory conduit, a transverse partition disposed in said conduit and having an opening therethrough, a valve disposed on the downstream side of said partition, a hollow imperforate, cylindrical, expansible and contractible thermostatic element disposed on the upstream side of said partition, said element having its upstream end fixed against movement, means connecting said element and said valve whereby contraction of said element causes said valve to seat against said partition and close said opening and expansion of said element opens said valve, and the area of such opening in said partition being materially greater than the effective area of said element, whereby pressure of liquid in said conduit tends to open said valve upon failure of the expandible element. 130
80
8. In apparatus of the character described, the combination of a circulatory conduit for liquid, a transverse partition disposed in said conduit and having an opening therethrough, a valve disposed on the downstream side of said partition, a hollow, imperforate, corrugated, cylindrical thermostatic element disposed on the upstream side of said partition, said element having its upstream end fixed and containing a volatile expansible fluid, means connecting said valve and element to maintain said element at not less than normal length when said valve is seated against said partition to close said opening, and the area of such opening in said partition being greater than the effective area of the downstream end of said element, whereby any pressure of circulating liquid 135
85

in said conduit will exert a pressure tending to open said valve.

9. In apparatus of the character described, the combination of a circulatory conduit for liquid, a transverse partition disposed in said conduit and having an opening therethrough, a valve disposed on the downstream side of said partition, a hollow, imperforate, corrugated, cylindrical thermostatic element disposed on the upstream side of said partition, said element having its upstream end fixed and containing a volatile expansible fluid at less than atmospheric pressure, means connecting said valve and element to maintain said element at not less than normal atmospheric pressure length when said valve is seated against said partition to close said opening, and the area of said opening in said partition being greater than the effective area of the downstream end of said element.

10. In apparatus of the character described, the combination of a circulatory

conduit for liquid, a transverse partition disposed in said conduit and having an opening therethrough, a valve disposed on the downstream side of said partition, a hollow, imperforate, corrugated, cylindrical thermostatic element having its upstream end fixed and containing a volatile expansible fluid, means connecting said valve and element to maintain said element at not less than normal atmospheric pressure length when said valve is seated against said partition to close said opening, and the area of such opening in said partition being greater than the effective area of the downstream end of said element, and the area of said valve exposed to the circulatory liquid when said valve is in closed position being materially less than the total area of said valve exposed to the liquid when said valve is in the open position.

Signed by me this 6th day of April, 1926.

WILLIAM R. ZIMMERMAN.
